Alex Beckers, of New York, N. Y.
Letters Patent No. 1086. Dated March 1, 1859.

The schedule referred to in these Letters Patent and making part of the same.

To all whom it may concern:

Be it known that I, A. Beckers, of the City, County and State of New York, have produced a new and Ornamental Design for Stereoscopic Case, and I do hereby declare that the following is a full, clear and exact description of the same, reference being had to the accompanying drawings making a part of this Specification, in which

Fig. 1. represents a Side elevation of my Stereoscopic case.

Fig. 2. is a vertical central section of ds. and

Fig. 3. is a horizontal section of the same.

Similar letters of reference in the three figures indicate corresponding parts.

This design consists in ornamenting the case by four columns placed on the four corners of the case - which support the top of the case so that the same rests on the capitals of the columns in the manner of an entablature consisting of the cornice only, (the architrave and frieze being omitted) the upper face of which cornice is made to incline towards each side, and to support the lid which opens in the centre being hinged at both ends and which is made to slope down from the centre towards two sides so as to give to the top a roof-like appearance.

A. is the case the sides of which consist of plain boards, the thickness of which however is increased at the under part of the case for about one third of its height by placing additional pieces a. a. on each side, so as to form the corner a', and columns B. are placed one on each corner of the case.

These columns approach the Tuscan order very closely, having a plain shaft b. which diminishes in size as it approaches the capital b' which consists of a square block, and which joins the shaft by a round convex moulding or bead b'' which is followed by a rectangular member or fillet b''' and the shaft rests on a base b* joining the same by a moulding b*' which consists of a narrow fillet joining a bead, and ending in a fillet or band of greater width which rests on the base.

The bases b* are square blocks which correspond in height with the corners a' of the case and which are placed on the corners of the case, so that their sides make angles of 135 degrees with the sides of the case, and so that the corners of the latter extend to the centre of the columns as represented in figs: 2 and 3.

The capitals b' support the entablature C, which rests on the same in the manner of a cornice which joins the sides of the case by a wavy moulding c. - The upper surface of this entablature is made to incline towards all four sides as represented in figure 1, and it supports the lid D. which is hinged to the upper surface of the entablature by means of ears d. d. so that it opens in the centre.

This lid is smaller than the entablature leaving that part of the same free which is made to incline towards the four sides of the case, and the two parts of the lid themselves are made to slope down from the centre, where one of the parts is provided with a round convex moulding d' and when the lid is closed the upper part of the case, which is supported by the columns has a roof-like appearance.

Two round projections E. E. are attached to one of the sides of the case, and near to its top which join the side by a fillet from which a Cyma recta, or wavy moulding leads to a fillet which is followed by a Scotia which joins another fillet and it ends

Des 1086

273

in a narrow head giving to the whole the appearance of the end of a telescope, and in fact these projections serve to hold the eyeglasses when the case is put into use.

What I claim as new and desire to secure by Letters Patent, is,

Forming a Case A, with the Columns B, the entablature C, and the lid D, arranged so as to form a new and Ornamental design, in the manner herein described.
